UNITED STATES PATENT OFFICE.

GIORGIO SEBASTIANO, OF ROCKWOOD, PENNSYLVANIA, ASSIGNOR OF ONE-THIRD TO ANTONIO BUFANO, OF DUNBAR, PENNSYLVANIA, AND ONE-THIRD TO ALFONSE BASILE, OF CONNELLSVILLE, PENNSYLVANIA.

TIE-PLATE.

1,177,362.

Specification of Letters Patent. Patented Mar. 28, 1916.

Application filed August 27, 1915. Serial No. 47,603.

To all whom it may concern:

Be it known that I, GIORGIO SEBASTIANO, a subject of the King of Italy, residing at Rockwood, in the county of Somerset and State of Pennsylvania, have invented certain new and useful Improvements in Tie-Plates, of which the following is a specification.

My invention relates to improvements in tie plates for railroad rails, and has for its object to provide a tie plate adapted to receive and support the flange and web of the rail upon the tie, in connection with co-acting supplemental bracing and supporting members, to fixedly hold the rail in position and prevent creeping.

One preferred form of the invention is illustrated in the accompanying drawing, in which—

Figure 1 is a plan view partially in section showing the application to one of the rails of a track of my invention. Fig. 2 is a view in side elevation corresponding to Fig. 1. Fig. 3 is an enlarged perspective detail view of the tie plate and its associated stay members in relative position. Fig. 4 is an enlarged cross section and detail view on the line 4—4 of Fig. 2.

Referring to the drawing, the tie plate in its entirety consists of a one-piece supporting slice or chair, preferably made of malleable steel or other suitable metal, having a base 2, adapted to lie upon the upper face and to be secured to the tie 3. At the inner side of the rail to be supported, the base 2 extends laterally providing a bottom 4, of substantially uniform thickness, adapted to intervene between the tie and the base of the rail, and to be spiked to the tie by one or

more spikes through one or more suitable openings 5. Said spike or spikes 6, which are driven in the usual manner, also engage the edge of the inner flange as clearly shown in Figs. 1 and 4. The outer portion of the

tie plate is reinforced, as clearly shown in Figs. 3 and 4, providing a substantial attaching portion having a plurality of bolt holes 7, one of which holes may extend through a supplemental extension 8 of the

tie plate as shown. Said reinforced portion of the plate is extended upwardly providing the vertical rail reinforcing and bracing wall 9 adapted to seat over the adjacent flange 10, web 11, and against the head 12

of the rail, as clearly shown in Fig. 4. A

reinforcing enlargement or rib 13 connects the main body portion of the plate 2 with such vertical portion 9, an intervening recess 14 being provided for receiving the lower edge of the outer stay member. Thus 60 constructed, the tie plate itself provides a substantial support for the rail, and is itself fixedly secured to the tie by the inner spike 6 and the outer spikes 15, which are driven into the tie through openings 7. Ordinarily, 65 such attachment to the tie does not prevent longitudinal creeping or other undesired movement of the rail, and for the purpose of preventing such movement, and of rigidly holding the tie plate and the rail itself 70 fixedly in position against movement under the several strains incident to traffic, I provide an outer stay member 16 and an inner stay member 17. These members as shown are 75 comparatively thin, and their middle portion is adapted to be arranged vertically flatwise, the one against the outer face of the vertical reinforcement 9 of the shoe; the other against the inner opposite face of rail web 11. For the purpose of cushioning the 80 inner stay member against the rail I preferably insert a strip 18 between said member and the rail web, as shown, which may be of wood, fiber, or other suitable material.

The several elements are fixedly connected 85 by a bolt 19, which extends through them and through an opening 20 in the vertical reinforcing portion 9 of the plate, so that when the nut of the bolt 19 is drawn up the several parts will be rigidly held. The seating of the middle strap portion 16 of the outer stay member in the recess 14 of the shoe, assists in its maintenance and relative holding action.

At each end the outer stay member 16 is 95 provided with attaching portions 21 adapted to be spiked to one or more of the ties, preferably two, at each side of the plate, longitudinally of the rail, by spikes inserted through openings 22. The inner stay 100 member 17 is similarly provided with extensions 23 at each end and similar securing spike holes 24. Extensions 21 and 23 are formed by bending the strip metal as indicated at 25, whereby to deflect it downwardly and outwardly, as clearly shown in Figs. 1 and 2, to proper position for attachment to the ties. As thus constructed and applied, it will be seen that the rail itself is 105 fixedly connected in position to the ties by 110

the several parts and will be positively held as stated.

An especial advantage of the construction, utilizing the shoe and stay members as arranged, is that the inner side of the rail is equally braced against creeping in either direction, by the inner stay member, while leaving ample clearance for the wheel flanges in passing over the rail.

10 The advantages of the invention will be readily appreciated by all those familiar with this class of mechanism. It is extremely simple and cheap in construction, very durable, not liable to get out of order, 15 and well adapted to the objects in view. It will be understood that the construction is intended to be applied to the several rails between the joints, one or more sets of shoes as shown being utilized as desired, although 20 I prefer to arrange the shoes in pairs as shown in Figs. 1 and 2, for the best results.

It will be understood that the invention may be variously changed by the skilled mechanic as to size, proportions, etc., to suit 25 the condition of use, but that all such changes are to be considered as within the scope of the following claims.

What I claim is:

1. A one-piece metallic tie plate having a 30 supporting base and a reinforcing portion at one side for engagement against the flange, web and head of a rail, and provided with a bolt opening for connection with the rail, and an integral reinforcing enlargement 35 providing between said reinforcing portion and enlargement a receiving groove for a stay member, and having base extensions at each side thereof provided with securing spike holes, substantially as set forth.

2. In combination, a one-piece tie plate 40 having a supporting and attaching base, an upwardly extending rail reinforcing member having a bolt opening and an integral reinforcing enlargement providing between said member and enlargement a receiving 45 groove for a stay member and a stay member engaging said groove and having terminal portions adapted to be attached to supplemental ties, substantially as set forth.

3. In combination with the ties and rail 50 of a track, a one-piece tie plate having a base adapted to be spiked to the tie provided with an upwardly extending reinforcing portion at one side of the rail, stay members arranged longitudinally to the rail at 55 each side thereof and secured to the ties beyond the tie plate, and a bolt extending through said stay members, tie plate member, and rail, substantially as set forth.

4. In combination with the ties and rail 60 of a track, a one-piece tie plate having a base adapted to be spiked to the tie provided with an inwardly and upwardly extending reinforcing portion at one side of the rail, stay members arranged longitudinally of the rail at each side of the rail and secured to the ties beyond the tie plate, a cushioning strip inserted between the rail web and one of said stay members, and a bolt extending through said stay members, 70 strip, tie plate member, and rail, substantially as set forth.

In testimony whereof I hereunto affix my signature in the presence of two witnesses.

GIORGIO SEBASTIANO.
